By Charles Lovett

Attorney

Patented Dec. 25, 1934. This is a continuation-in-part of my application for a patent filed in the United States Patent Office on June 1, 1932, Serial No. 620,352, now pending. The present application is for a window which will open in any direction, and which will be held in any position desired.

UNITED STATES PATENT OFFICE

1,985,877

WINDOW

Ira Loew, Lynn, Mass.

Application May 7, 1934, Serial No. 724,352

4 Claims. (Cl. 20—40)

This invention relates to windows and more particularly to what I term a four way window.

It has for its objects to provide a window, and operating means therefor, capable of opening 5 the window to various extents and holding the window open at any extent desired, or closed; to provide a window which will open to the east, or to the west to catch the wind direction, or at the top to admit the unobstructed sunshine, or 10 from the bottom to shed the rain, and all for a better and improved ventilation under varying conditions, and to provide the various other advantages and results made evident from the following specification.

Referring to the accompanying drawing which forms a part of this specification, and in which similar letters of reference refer to similar parts throughout the various views. Figure 1 is a front view of my improved window in closed position. Figure 2 is a horizontal sectional view on line 2—2 in Figure 1. Figure 3 is a vertical sectional view on line 3—3 in Figure 1, with the window open at one of its various positions. Figures 1, 2, and 3 show one embodiment 25 of the operating mechanism which is capable of modification.

Referring again to the drawing, it will be seen that the window is provided with an inner and an outer sash, the inner sash for opening purposes, and the outer, a circular sash, adaptable for turning in the casing within which it is mounted, for the purpose of enabling the inner sash, which is mounted upon the outer sash, to open in any and all directions. A shows the 30 window frame which may optionally be fixed by the bolts A¹ to the structure upon which the window is used, or hinged thereto as shown, Figure 1, by the hinges A². When hinged, the bolts A¹ are not required but a locking device A³, of any approved type is placed on the side of the window opposite the hinges A². The outer circular sash B is flanged at B¹ to fit a groove A⁵ in the frame A and is held in position within the groove by the cap B². A series of screws B³ function to hold the cap in proper place. Thus secured, the circular sash B is readily revolved in the groove A⁵ in the sash A in either direction by applying pressure on the knobs B⁴. The sash B is adaptable to make a complete or partial 45 revolution as desired. The inner window C, preferably square in shape, is hinged upon the circular sash B at C² by spring hinges of any approved type which normally tend to swing the window open. To control the opening tendency 50 of the spring hinges the sash C is held in closed

position, or in any desired open position, by flexible cords D and D² one end of each being attached to a corner of the sash C opposite the hinged side C². The cords D and D² pass through orifices at D³ and D⁴ in the circular sash B, over respectively the pulleys E and F and then to the drums H and I. The drums H and I are fixed respectively to the gears J and K which are so mounted as to be driven by the gear L. The gear L is operated by the handle L² and the ratchet 10 wheel L³. The pawl L⁴ locks the gears in any desired position. As the handle L² is turned the flexible cords D and D² are wound or unwound upon the drums and either allows the spring 15 hinges at C² to open the window frame C, or pull against said spring and close the window.

While I have illustrated and described a preferred construction for carrying my invention into effect, this is capable of variation or modification without departing from the spirit of the 20 invention. I, therefore, do not wish to be limited to the exact details of construction herein set forth but desire to avail myself of such variations and modifications as come within the scope 25 of the appended claims.

Having thus described the invention, I claim as new and desire to secure by Letters Patent of the United States of America:

1. A window assembly comprising a holding frame, an inner and an outer sash, said outer sash being circular in form and mounted in and adapted to turn within said holding frame, means 30 for turning said circular sash within said holding frame, said inner sash hinged to said circular frame, and means for opening, closing, and holding in fixed position said inner sash.

2. A window assembly comprising a holding frame, an inner and an outer sash, said outer sash being circular in form and mounted in and adapted to turn within said holding frame, said inner sash hinged to said circular frame, means for opening, closing, and holding in fixed position 40 said inner sash, said holding sash adapted to be hinged to a structure upon which it is used.

3. A window assembly comprising a holding 45 frame, an inner and an outer sash, said outer sash being circular in form and mounted in and adapted to turn within said holding frame, spring hinges secured to said inner sash and said circular sash so that the inner sash has a normal 50 tendency to open and means for controlling said normal tendency and to hold said inner sash in fixed position.

4. A window assembly comprising a holding frame, an inner sash, an outer circular sash 55

mounted in and adapted to turn within said holding frame, means for turning said circular sash within said holding frame, spring hinges secured to said inner sash and to said circular sash so that the inner sash has a normal tendency to open, and means for controlling said normal

tendency and to hold said inner sash in fixed position, said last mentioned means comprising a flexible connection, a series of pulleys, drums, gears, ratchet wheel, pawl, and operating handle.
